BRUSH

Carl J. Nagl, Omaha, Nebr., assignor to Northam Warren Corporation, New York, N. Y., a corporation of New York

Application May 26, 1934, Serial No. 727,699

4 Claims. (CL 15—143)

This invention relates to improvements in brushes and has for its object more particularly the provision of a novel form of camel's hair brush or the like made with a metal shaft and adapted to be securely held in the cap of a bottle.

A particular object of this invention is the provision of a new form of camel's hair brush or the like in which the shaft or handle is made from one piece of metal in which the brush fibres will be securely held and in which the end of the brush will be so constructed that it can be securely and accurately secured to the cap of the bottle in which it is placed.

15 Further objects will be apparent from the specification and drawing in which:—

Fig. 1 is a perspective view of one form of blank before forming into tubing.

Fig. 2 is a perspective view of the same blank after the first operation.

Fig. 3 is the formed tubing shown in perspective.

Fig. 4 is a vertical section of the cap and a side view of the brush with bristles secured therein showing the brush and handle partly introduced into the bottle cap.

Fig. 5 is a sectional view of the cap and brush assembled.

Fig. 6 is a plan view of another form of blank from which the tube can be made.

Fig. 7 is a side view in elevation of the tube formed from the blank shown in Fig. 6.

In Fig. 1, there is illustrated an elongate blank 8 of sheet metal or equivalent material provided at one end with rounded corners 11, 11', a trimmed or tapered portion 10, and a laterally extended lip adapted to lap over the other side edge of the blank when rolled into tube form. Fig. 2 indicates the U-shaped form of the tube after the first shaping operation; Fig. 3, the tube or handle after the second shaping operation in which the large end of the tube 14 is cylindrical and is defined by the butt seam 15 and the small end of the tube 16' is tapered and defined by an overlapping seam.

45 This is the important feature of this invention, to form the blank at the smaller end with an overlapping seam and to form the large end of the blank with a butt seam edge to edge, instead of having one continuous butt seam or one continuous overlapping seam for the entire shaft.

The provision of the lap seam in the tapered or shank portion of the brush handle, as will be self-apparent, provides a material amount of reinforcement therein, which reinforcement at this

portion of the handle is of importance, due to the fact that therein is localized stress tending to buckle the handle during use or abuse. In addition, the extension of the lap joint to the extreme small end of the device affords a socket for the bristles 17 which, when constricted or punched together as shown, will permanently maintain the arrangement of the several bristles in proper brush form, as well as assure against loosening and shedding thereof.

The importance of the butt seam which defines the cylindrical portion 14 of the handle lies in the fact that the cylindrical portion is smooth and true and readily insertable within the well 20 of the cap 19. Moreover, the association of the cylindrical handle portion 14 with the well 20 of the cap 19 is characterized by a snug fit and the edges of the portion 14 being in abutting relation resist stresses tending to constrict the cylindrical portion 14 and loosen its fit within the cap well 20. Assurance against unintentional disassociation of brush and cap members is thus afforded in a manner well adapted to large scale production of the item.

Referring more specifically to Figs. 4 and 5, the cap element 19 is provided, in addition to the inwardly projecting cylindrical socket 21 having the well or bore 20, with a threaded skirt 22 adapted to be threadedly engaged about the neck of a conventional bottle or other receptacle, (not shown).

In the modified form of my invention illustrated in Figs. 6 and 7, the handle blank 23 consists of a parallel-edged portion 24 terminating at 25, and a trimmed or tapered portion 26. 27 and 27' are the rounded-off corners of the portion 24. The blank shown in Fig. 6 is curled into tubular form as shown in Fig. 7, the portion 24 becoming the cylindrical portion 28 of the finished handle defined by the butt seam 29. 30 is the tapered tubular portion having the lap seam 31.

The advantage of the form of blank shown in Figs. 1 and 6 is that it provides, in effect, a reduced or pointed tip on the cylindrical part of the tube, thus facilitating insertion of the handle end in the cap socket portion 21 of the cap. In both modifications herein described it will be noted that the blank employed is such that the butt-seam-defined portion of the handle is cylindrical and will have snug and substantially complete contact with the inner surface of the socket portion 21 of the cap 19.

It is obvious that changes may be made in the form of the handle and the length of the

respective butt seams and lap seams without de-parting from the spirit of my invention.

What I claim is:—

1. A handle for a brush or similar applicator comprising a one piece, quill-like, tubular member formed of sheet stock and provided with a longitudinal seam extending the full length thereof, said tubular member having one end formed to receive and secure the brushing element proper, an integral cylindrical grip portion at the other end defined by an abutting portion of said longitudinal seam, and a shank portion of reduced diameter intermediate said cylindrical and brush-element-receptive portion, said shank portion being of tapering form and defined by a lapped portion of said longitudinal seam.
2. A handle for a brush or similar applicator comprising a one piece, quill-like, tubular member formed of sheet stock and provided with a longitudinal seam extending the full length thereof, said tubular member having one end formed to receive and secure the brushing element proper, an integral cylindrical grip portion at the other end defined by an abutting portion of said longitudinal seam, said cylindrical portion being diagonally cut away at its extremity to provide, in effect, a tip of slightly tapered form adapted to facilitate insertion of said cylindrical portion within a member having a complementary cylindrical bore, and a shank portion of reduced diameter intermediate said cylindrical and brush-element-receptive portion, said shank portion being of tapering form and defined by a lapped portion of said longitudinal seam.

25

3. A handle for a brush or similar applicator comprising a one piece, quill-like, tubular member formed of sheet stock and provided with a longitudinal seam extending the full length thereof, said tubular member having one end formed to receive and secure the brushing element proper, an integral cylindrical grip portion at the other end defined by an abutting portion of said longitudinal seam, said cylindrical portion being notched at its extremity to provide, in effect, a tip of slightly tapered form adapted to facilitate insertion of said cylindrical portion within a member having a complementary cylindrical bore, and a shank portion of reduced diameter intermediate said cylindrical and brush-element-receptive portion, said shank portion being of tapering form and defined by a lapped portion of said longitudinal seam.

10

15

4. A handle for a brush or similar applicator comprising a one piece, quill-like, tubular member formed of sheet stock and provided with a longitudinal seam extending the full length thereof, said tubular member having a cylindrical grip portion at one end thereof defined by an abutting portion of said longitudinal seam, a constricted socket portion at its other end for retaining the brush element proper, the longitudinal seam in said socket portion having the form of a lap-joint, and an integral shank portion intermediate said cylindrical and socket portion, said shank portion being of tapered form and, like said socket portion, being defined by a lap-joint portion of said longitudinal seam.
